ROLLING TOY

Michael Tannen, New York, N.Y.

Application August 8, 1952, Serial No. 303,335

11 Claims. (Cl. 46—207)

1

This invention relates to toys.

It is particularly directed to a rolling toy having means controlled by rolling the toy in one direction to cause the toy to roll back.

Rolling toys have been known which will roll back when rolled on a floor. Also rolling toys have been known which when rolled in one peripheral direction will roll back but when rolled in the opposite peripheral direction will not roll back. In accordance with the present invention, there is provided a rolling toy which may be rolled in either peripheral direction on a floor and will roll back, the toy being provided with means to prevent rolling back when rolled in either peripheral direction.

A further object of this invention is to provide a rolling toy at the axis of which is supported a rubber band from which is suspended a weight so that when the toy is rolled the rubber band is twisted and when the toy comes to a stop, the twisted rubber band will roll the toy backward, means controlled by the operator being provided, however, to cause the weight to turn with the rolling toy so as to not to twist the rubber band when the toy is rolled so that the toy will not roll back.

An object of this invention is to provide a toy of the character described which will be in the nature of puzzle in that the user can roll the toy away and have it return to him, and yet by merely casually tilting the barrel before giving it to a spectator, the latter cannot get the toy to return.

Yet another object of this invention is to provide a rolling toy of the character described which may be in the shape of a hollow barrel provided with a pair of transverse partitions formed with lugs at the axis interconnected by a rubber band, and a weighted member suspended from the rubber band so that when the barrel is rolled, the weight remains suspended and twists the rubber band, longitudinally slideable pins being mounted on said partitions, said pins being so arranged that when any of the pins on either of the partitions slide inwardly into the plane of the weight, said pin or pins will rotate the weight together with the barrel when the latter is rolled so as to prevent the rubber band from becoming twisted, the pins being adapted to slide outwardly out of the path of the weight by twirling the barrel about an axis perpendicular to the longitudinal axis of the barrel and passing through the center of the barrel due to centrifugal force, and the pins being slideable inwardly into the path of the weight by merely

2

tilting the barrel either up or down. The tilting may be done casually without the spectator noticing it thereby creating a mystery in the operation of the toy.

Still another object of this invention is to provide a strong, rugged and durable device of the character described, which will be relatively inexpensive to manufacture, easy to manipulate, amusing, educational and puzzling to play, and which shall yet be practical and efficient to a high degree in use.

Other objects of this invention will in part be obvious and in part be hereinafter pointed out.

The invention accordingly consists in the features of construction, combinations of elements, and arrangement of parts, which will be exemplified in the construction hereinafter described, and of which the scope of invention will be indicated in the following claims.

20 In the accompanying drawing in which are shown various illustrative embodiments of this invention:

Fig. 1 is a front elevational view of a toy embodying the invention;

Fig. 2 is an end view thereof;

Fig. 3 is a cross sectional view taken on the line 3—3 of Fig. 2;

Fig. 4 is a cross sectional view taken on the line 4—4 of Fig. 3;

Fig. 5 is a cross sectional view taken on the line 5—5 of Fig. 3;

Fig. 6 is a cross sectional view taken on the line 6—6 of Fig. 3.

Referring now in detail to the drawing, 35 Fig. 1 designates a toy embodying the invention. The same comprises a barrel shaped shell 10a which may be constructed of synthetic plastic material or any other suitable material.

While the shell is shown to resemble a barrel, it will be appreciated that it may be formed in any other suitable shape as long as it can roll about its axis. The shell 10a comprises a pair of similar symmetrically disposed end members 11, an intermediate member 12 and an inner transverse partition 12a.

End members 11 are comprised of annular depressed end walls 13. Extending from end walls 13 are annular flanges 14, which taper curvedly and outwardly. At each of their widest end portions 15 is an overlying annular projection 16 which simulates the hoops of a barrel, and the inner edge portions of said annular projections 16 being formed with annular shoulder portions 17.

Intermediate member 12 is comprised of an

annular wall 18, and an annular sleeve 19 extending therefrom, said sleeve 19 having its outer surface slightly curved to form a continuous curvature effect with annular flanges 14. At the outer juncture of annular wall 18 and sleeve 19, 5 is an annular groove 20 which is fitted into juxtaposition with annular shouldered portion 17 of an end member 11, where it is secured by acetone, cement or other fixing agent. The bottom surface 21 of sleeve 19 contacts the bottom 10 surface 22 of the second end member 11 and is secured thereto, and projects slightly beyond the annular shouldered portion 17 therein to form a pocket 22a.

Annular wall 18 is comprised of an opening 23 which is centrally located and comprises a semi-arcuate portion 24 and parallel tangential sides 25 and two straight, aligned bottom portions 26. Within said cut portions and forming the other edges of the opening 23 is a hook 27 comprising a shank 28 and a mushroom top 29. It is thus seen that hook 27 is centrally located within opening 23 for the purposes hereinafter mentioned. Also on annular wall 18, there are three through holes 30 equally spaced apart and from said opening 23. On the surface of wall 18 and extending into the area 31 between said wall 18 and end wall 13, and concentric to and spaced from each hole 30 is a vertical outwardly extending annular hollow sleeve 32.

Slidable within the hollow sleeve 32 is a pin 33. Said pin 33 is comprised of a tubular shank 34 which passes through hole 30, and an annular shaped head 35, which is in the area 31, and whose diameter is equal to that of the hollow portion of sleeve 32. The length of said pin 33 is longer than the distance from wall 18 to end wall 13 and as the head 35 is wider than hole 30. It is clear that the pins 33 are only movable through holes 30 and will not fall out therefrom. The purposes of said pins 33 will be hereinafter mentioned.

Member 12a is comprised of an annular wall 36. At the outer edge thereof is an annular lip 37 which fits into the pocket 22a formed by and 45 contacts bottom surface 21 of sleeve 19, and annular shouldered portion 17 of the second end member 11, and is secured thereto by acetone, cement or other fixing agent. Said annular wall 36 is also comprised of an opening 38, similar to opening 23 of wall 18. However, opening 38 is located 180° away from opening 23. Thus, the mushroom head of hook 27 would be facing in one direction, and the mushroom head 39 of the hook 43 in opening 38 would be facing in the opposite direction therefrom, although their respective shanks 28 and 41 are parallel to each other. Annular wall 36 is comprised of three through holes, three concentric and hollow sleeves therearound, and three pins slidable in said holes, similar to the construction of the component parts on and appurtenant to wall 18 as heretofore described.

Extending between said hooks 27 and 40, and fitting around their respective shanks and under their respective mushroom heads is an elastic rubber band 42. Suspended on said rubber band 42 midway between said walls 18 and 36 is a weight 43. Said weight 43 comprises a head portion 44 and a lower, larger portion 45. Said 55 head portion 44 comprises an annular groove 46 therein into which the said rubber band 42 fits allowing said weight 43 to be freely suspended thereon. Along the outer surfaces of said annular flanges 14 and annular sleeve 19 are continuous

longitudinal shallow grooves 47 to give the effect of separate staves of a barrel, said markings being interrupted only by said annular projections 16 which give the appearance of barrel hoops.

It is thus seen that the said weight 43 is freely suspended on said rubber band 42 to allow the latter to be wound when pins 33 are in their outward position. Such positioning of the pins can be accomplished by merely spinning the barrel on its vertical axis, so that the pins are flung outwardly due to centrifugal force. When the barrel is in such condition and is rolled any distance in any peripheral direction it should be understood that the weight remains in a stationary position and the rubber band becomes wound up thus creating a certain torsion. When the forces of friction finally stop the barrel, the wound rubber band's torsion begins to unwind it thus causing the barrel to roll back towards the point or place of beginning.

After such a demonstration, a demonstrator casually picks up the barrel so that either end is facing up, which permits the pins at either end to slide inwardly. The barrel is then handed to one who wishes to try the trick. On rolling the barrel with the pins in this "in" position however, the pins come in contact with the weight and so force it to rotate with the barrel and thus preventing any winding of the rubber band. Thus, in this case, to the dismay of the experimenter, when friction stops the barrel, it will not roll back to the point or place of beginning.

It is of course understood that various changes and modifications may be made in the details of construction and materials comprising the above and not specifically described in the embodiment of this invention without departing from the spirit thereof.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A rolling toy comprising a shell adapted to roll about its axis on a floor or surface, an elastic member at the axis of said shell, means to anchor the ends of said elastic, a weight suspended from said elastic and between said anchoring means, whereby when said shell is rolled on the floor or surface the elastic member will become twisted to create torsion force for rolling the shell back after the shell stops rolling, and means in the shell to cause the suspended weight to turn with the shell when the shell is rolled so as to prevent the elastic member from being twisted so that the toy will not roll back.

2. A toy comprising a shell adapted to be rolled, means within said shell to cause it to roll back, said means within the shell to cause it to roll back comprising two partition walls, an elastic band interconnecting said partition walls and a freely swinging weight mounted on said elastic band which on the roll away from a point of beginning remains stationary while the barrel rotates, turning the elastic band on each side of the

weight to wind the same, and which rubber band unwinds when the toy is stopped by friction, to cause the barrel to rotate in the opposite direction and cause the toy to roll back, and centrifugal means in the shell to cause the weight to turn with the shell when the latter is rolled.

3. A toy comprising a shell adapted to be rolled, means within said shell to cause it to roll back and means within said shell to prevent said toy from rolling back, said means within the shell to cause it to roll back comprising two partition walls, an elastic band interconnecting said partition walls and a freely swinging weight mounted on said elastic band on each side of the weight to wind the same, and which rubber band unwinds when the toy is stopped by friction, to cause the barrel to rotate in the opposite direction and cause the toy to roll back, and said means to prevent said toy from rolling back comprising pins slidably mounted in said partition walls, which pins when in preventing position, are in contact with said weight, forcing it to rotate with the barrel to prevent the elastic band from being wound.

4. A toy, adapted to be rolled in one direction and means therein to cause said toy to roll back and optional means in said toy to prevent said toy from rolling back, said toy comprising a shell formed of four separate parts secured together to form an outward appearance of a barrel, said four parts being two end members, an intermediate member and an inner transverse partition, each of said end members comprising an annular depressed end wall, an annular curved, outwardly tapering flange leading therefrom, an overlying annular projection at the widest end portion of said flange and an annular shouldered portion around the inner edge portions of said annular projections, said annular projections simulating barrel hoops.

5. A toy, adapted to be rolled in one direction and means therein to cause said toy to roll back and optional means in said toy to prevent said toy from rolling back, said toy comprising a shell formed of four separate parts secured together to form an outward appearance of a barrel, said four parts being two end members, an intermediate member and an inner transverse partition, each of said end members comprising an annular depressed end wall, an annular curved, outwardly tapering flange leading therefrom, an overlying annular projection at the widest end portion of said flange and an annular shouldered portion around the inner edge portions of said annular projections, said annular projections simulating barrel hoops, and said intermediate member comprising an annular wall and an annular sleeve extending therefrom, the outer sleeve having a slightly curved outer surface to form a continuous curvature with the annular flanges of the end members, an annular groove at the juncture of the annular wall and an annular sleeve, which is secured in the said annular shouldered portion of the first of said end members and the bottom surface of said sleeve contacting the bottom edge of the second end member and forming a pocket with the said annular shouldered portion thereof, said annular wall of said intermediate member comprising a centrally located opening, with an extending mushroom headed hook therein, three through openings equally spaced from each other and from said centrally located opening, a vertical, hollow sleeve spaced from and concentric to each of said holes extending from the surface of said annular wall into the space formed between said annular wall of the said intermediate member and the annular end depressed wall of said first end member secured to said intermediate member, and said inner transverse partition comprising an annular wall and an annular lip at its outer edge which is secured in the aforesaid pocket, and said inner wall member having a centrally located opening with an extending mushroom headed hook therein located in a position, 180° removed from said mushroom headed hook of said intermediate member, three through openings equally spaced from each other and from said centrally located opening, a vertical hollow sleeve spaced from and concentric to each of said holes extending from the surface of said annular wall in a direction opposite to that of the said hollow sleeves of the said intermediate member, longitudinal shallow grooves on the outer surfaces of said annular curved, outwardly tapering flanges of said end members and on said annular sleeve extending from said annular wall of said intermediate member to give the effect of separate barrel staves.

of said annular wall into the space formed between said annular wall of the said intermediate member and the annular end depressed wall of said first end member secured to said intermediate member.

6. A toy, adapted to be rolled in one direction and means therein to cause said toy to roll back and optional means in said toy to prevent said toy from rolling back, said toy comprising a shell formed of four separate parts secured together to form an outward appearance of a barrel, said four parts being two end members, an intermediate member and an inner transverse partition, each of said end members comprising an annular depressed end wall, an annular curved, outwardly tapering flange leading therefrom, an overlying annular projection at the widest end portion of said flange and an annular shoulder portion around the inner edge portions of said annular projections, said annular projections simulating barrel hoops, and said intermediate member comprising an annular wall and an annular sleeve extending therefrom, the outer sleeve having a slightly curved outer surface to form a continuous curvature with the annular flanges of the end members, an annular groove at the juncture of the annular wall and an annular sleeve, which is secured in the said annular shoulder portion of the first of said end members and the bottom surface of said sleeve contacting the bottom edge of the second end member and forming a pocket with the said annular shoulder portion thereof, said annular wall of said intermediate member comprising a centrally located opening, with an extending mushroom headed hook therein, three through openings equally spaced from each other and from said centrally located opening, a vertical, hollow sleeve spaced from and concentric to each of said holes extending from the surface of said annular wall into the space formed between said annular wall of the said intermediate member and the annular end depressed wall of said first end member secured to said intermediate member, and said inner transverse partition comprising an annular wall and an annular lip at its outer edge which is secured in the aforesaid pocket, and said inner wall member having a centrally located opening with an extending mushroom headed hook therein located in a position, 180° removed from said mushroom headed hook of said intermediate member, three through openings equally spaced from each other and from said centrally located opening, a vertical hollow sleeve spaced from and concentric to each of said holes extending from the surface of said annular wall in a direction opposite to that of the said hollow sleeves of the said intermediate member, longitudinal shallow grooves on the outer surfaces of said annular curved, outwardly tapering flanges of said end members and on said annular sleeve extending from said annular wall of said intermediate member to give the effect of separate barrel staves.

7. A toy, adapted to be rolled in one direction and means therein to cause said toy to roll back and optional means in said toy to prevent said toy from rolling back, said toy comprising a shell formed of four separate parts secured together to form an outward appearance of a barrel, said four parts being two end members, an intermediate member and an inner transverse partition, each of said end members comprising an annular depressed end wall, an annular curved, outwardly tapering flange leading there-

from, an overlying annular projection at the widest end portion of said flange and an annular shoulder portion around the inner edge portions of said annular projections, said annular projections simulating barrel hoops, and said intermediate member comprising an annular wall and an annular sleeve extending therefrom, the outer sleeve having a slightly curved outer surface to form a continuous curvature with the annular flanges of the end members, an annular groove at the juncture of the annular flanges of the end members, an annular groove at the juncture of the annular wall and an annular sleeve, which is secured in the said annular shoulder portion of the first of said end members and the bottom surface of said sleeve contacting the bottom edge of the second end member and forming a pocket with the said annular shoulder portion thereof, said annular wall of said intermediate member comprising a centrally located opening, with an extending mushroom headed hook therein, three through openings equally spaced from each other and from said centrally located opening, a vertical, hollow sleeve spaced from and concentric to each of said holes extending from the surface of said annular wall into the space formed between said annular wall of the said intermediate member and the annular end depressed wall of said first end member secured to said intermediate member, and said inner transverse partition comprising an annular wall and an annular lip at its outer edge which is secured in the aforesaid pocket, and said inner wall member having a centrally located opening with an extending mushroom headed hook therein located in a position 180° removed from said mushroom headed hook of said intermediate member, three through openings equally spaced from each other and from said centrally located opening, a vertical hollow sleeve spaced from and concentric to each of said holes extending from the surface of said annular wall in a direction opposite to that of the said hollow sleeves of the said intermediate member, longitudinal shallow grooves on the outer surfaces of said annular curved, outwardly tapering flanges of said end members and on said annular sleeve extending from said annular wall of said intermediate member to give the effect of separate barrel staves and said means to cause said top to roll back towards the place of beginning comprising a rubber band stretched between said intermediate member and said inner transverse partition and being placed around the respective mushroom headed hooks therein, a weight with a large portion and a smaller head portion having a groove on each side thereof and an overlying upper lip thereover, said weight freely suspended on said rubber band which runs through the grooves on either side of said weight and which weight remains stationary on the rubber band causing the rubber band on either side of it to be wound on any peripheral roll of said toy, and the unwinding of said rubber band causing the toy to roll back.

8. A toy adapted to be rolled in one direction and means therein to cause said toy to roll back and optional means in said toy to prevent said toy from rolling back, said toy comprising a shell formed of four separate parts secured together to form an outward appearance of a barrel, said four parts being two end members, an intermediate member and an inner transverse partition, each of said end members comprising an annular depressed end wall, an annular curved, outwardly tapering flange leading therefrom, an overlying annular projection at the widest end portion of

said flange and an annular shoulder portion around the inner edge portions of said annular projections, said annular projections simulating barrel hoops, and said intermediate member comprising an annular wall and an annular sleeve extending therefrom, the outer sleeve having a slightly curved outer surface to form a continuous curvature with the annular flanges of the end members, an annular groove at the juncture of the annular wall and an annular sleeve, which is secured in the said annular shoulder portion of the first of said end members and the bottom surface of said sleeve contacting the bottom edge of the second end member and forming a pocket with the said annular shoulder portion thereof, said annular wall of said intermediate member comprising a centrally located opening, with an extending mushroom headed hook therein, three through openings equally spaced from each other and from said centrally located opening, a vertical, hollow sleeve spaced from and concentric to each of said holes extending from the surface of said annular wall into the space formed between said annular wall of the said intermediate member and the annular end depressed wall of said first end member secured to said intermediate member, and said inner transverse partition comprising an annular wall and an annular lip at its outer edge which is secured in the aforesaid pocket, and said inner wall member having a centrally located opening with an extending mushroom headed hook therein located in a position 180° removed from said mushroom headed hook of said intermediate member, three through openings equally spaced from each other and from said centrally located opening, a vertical hollow sleeve spaced from and concentric to each of said holes extending from the surface of said annular wall in a direction opposite to that of the said hollow sleeves of the said intermediate member, longitudinal shallow grooves on the outer surfaces of said annular curved, outwardly tapering flanges of said annular wall of said intermediate member to give the effect of separate barrel staves and said means to cause said top to roll back to the place of beginning comprising a rubber band stretched between said intermediate member and said inner transverse partition and being placed around the respective mushroom headed hooks therein, a weight with a large portion and a smaller head portion having a groove on each side thereof and an overlying upper lip thereover, said weight freely suspended on said rubber band which runs through the grooves on either side of said weight and which weight remains stationary on the rubber band causing the rubber band on either side of it to be wound on any peripheral roll of said toy, and the unwinding of said rubber band causing the toy to roll back, and said optional means in said toy to prevent said toy from rolling back towards the place of beginning comprising pins slidably mounted in said through holes and through said hollow sleeves surrounding each of said through holes, each of said pins comprising a shank and head, the head being greater in diameter than the said through hole through which said pin slides and being equal in diameter to the hollow of the sleeves surrounding said hole, and the length of said pin being longer than the distance from the through hole to the annular depressed end wall, said pins being optionally moved to contact said weight and force the same to rotate at the same rate as and with the toy and so preventing the

rubber band from becoming wound up on rolling in any peripheral direction.

9. A toy having the outward appearance and shape of a barrel and comprising an outer shell, end walls and two inner walls, means to cause said toy to roll back toward a place from where it was originally rolled in any peripheral direction and means to prevent the roll back of the toy when rolled in any peripheral direction, and each of said inner walls comprising a centrally located opening with a projection remaining in said space, and lying along the transverse axis of said toy located about said opening, and said means to cause said toy to roll back, comprising a rubber band attached to said hooks and a weight having a groove on each side, suspended from said rubber band so that the rubber band goes through each groove of the weight permitting the rubber band to be wound when the toy is rolled in any peripheral direction.

10. A toy having the outward appearance and shape of a barrel and comprising an outer shell, end walls and two inner walls, means to cause said toy to roll back toward a place from where it was originally rolled in any peripheral direction and means to prevent the roll back of the toy when rolled in any peripheral direction, and each of said inner walls comprising a centrally located opening with a projection remaining in said space, and lying along the transverse axis of said toy located about said opening, and said means to cause said toy to roll back, comprising a rubber band attached to said hooks and a weight having a groove on each side, suspended from said rubber band so that the rubber band goes through each groove of the weight permitting the rubber band to be wound when the toy is

rolled in any peripheral direction, and said means to prevent the roll back of said toy, comprising means slidable within said through openings to force said weight to rotate with the toy when the toy is rolled in any peripheral direction.

- 5 11. A toy comprising a sealed, wholly closed shell adapted to be rolled about its axis on a floor or flat surface, means in the shell to cause the shell to roll back when the shell is rolled on said floor or surface in either peripheral direction, and means within the shell to prevent rolling back of the toy by said first means within the shell when the toy is rolled on said floor or surface in either direction, said roll back means 10 comprising an elastic member at the axis of the shell, means to anchor the ends of the said elastic, a weight suspended on said elastic between said anchoring means, said preventing means comprising a plurality of members slidably mounted 15 within the shell into and out of the plane of said suspended weight, and said slidable members being adapted to be moved out of the plane of said suspended weight upon twirling the shell about an axis perpendicular to the axis of the 20 shell.

25 MICHAEL TANNEN.
